UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR A PLUG-CLUSTER.

56,721.

Specification for Design.

Patented Dec. 7, 1920.

Application filed February 2, 1920. Serial No. 355,777. Term of patent 14 years.

To all whom it may concern:

Be it known that I, REUBEN B. BENJAMIN, a citizen of the United States, residing at Chicago, in the county of Cook and State of Illinois, have invented a new, original, and ornamental Design for a Plug-Cluster, of which the following is a specification, reference being had to the accompanying drawing, forming a part thereof.

The figure shows a side elevation of a pull-switch swivel shell plug cluster.

In order to give a clearer understanding of the construction than could be obtained from the drawing, it is stated that the stippled part of the drawing may be porcelain or other insulating material.

I claim:

The ornamental design for a plug cluster, substantially as shown.

REUBEN B. BENJAMIN.
